CLAIM

The ornamental design for a display screen or portion thereof with animated graphical user interface, as shown and described.

DESCRIPTION

1. Display screen or portion thereof with animated graphical user interface

2. Display screen or portion thereof with animated graphical user interface

1.1 : First image

1.2 : Second image

1.3 : Third image

2.1 : First image

2.2 : Second image

2.3 : Third image

The appearance of the transitional image sequentially transitions between the images shown in reproductions 1.1-1.3 and 2.1-2.3. The process or period in which one image transitions to another forms no part of the claimed design.

1 Claim, 6 Drawing Sheets
